United States Patent Office.

EDGAR R. HALL AND WILLIAM H. TOWN, OF SYRACUSE, NEW YORK,
SAID HALL ASSIGNS HIS RIGHT TO SAID TOWN.

Letters Patent No. 100,753, dated March 15, 1870.

IMPROVEMENT IN DEVICE FOR OPERATING CHURNS.

The Schedule referred to in these Letters Patent and making part of the same.

To all whom it may concern:

Be it known that we, EDGAR R. HALL and WILLIAM H. TOWN, of Syracuse, in the county of Onondaga, and State of New York, have invented a new and useful Improvement in Devices for Operating Churns; and we do hereby declare the following to be a full, clear, and exact description of the construction and operation of the same, reference being had to the annexed drawings, making part of this specification.

To enable others to make and use our invention, we will proceed to describe its construction and operation.

The nature of our invention consists in the combination and arrangement of the several parts of the machine for operating churns, as hereinafter fully described.

In constructing our invention, make the wooden frame A, having upright posts A', between which a rock-shaft, C, is placed to support the arm D, which are connected to the swivels E by the pins G. These swivels hold around the neck at the upper end of the dash-handle P'.

The dash-handles pass loosely through the hubs H, which are attached to the frame at I by the set-screws J.

On the top of the hubs rest the loose pulleys K, which are grooved on the edge to receive the cord R.

On the crank-shaft N' is the double-grooved pulley N, around which the cords R pass from the loose pulleys K.

The cords R are made of elastic material.

The pitman L is connected at its upper end to the arm T by the pin U, and at its lower end to the double crank V.

The operation of the device is as follows:

By turning the hand-crank W the whole machine is set in motion.

By the pitman L and arm T, the rock-shaft is operated, and an up-and-down motion communicated to the churn-dashers P.

By the pulleys and cords the dashers P are made to revolve at the same time that they are under the up-and-down motion.

The loose pulleys K have a small pin, X, projecting inwardly and into the grooves Y in the dash-handles P', by which the dash is made to revolve.

The extent of motion in the dasher may be adjusted to suit a large or small amount of cream in a churn, by shifting the attachment of the swivels E to the arms D, and, at the same time, shifting the position of the hubs H toward or from the center of the machine by means of the set-screw J.

The elasticity of the cords R adapting their length to the position of the pulleys K and hubs H.

The device being double, is intended either for operating one or two churning by the dashers P, and by giving both a revolving and an up-and-down motion to the dashers, the churning is accomplished far more rapidly than with a single motion in the dashers.

What we claim as of our invention, and desire to secure by Letters Patent, is—

The combination and arrangement of the crank-shaft and pulley N, the pitman L, the rock-shaft O, arms D, balance-wheel O, grooved churn-dash P, swivel E, and the elastic band R; when the dash is made adjustable, and the double action is communicated to it, substantially as set forth.
